ADJUSTABLE CORRECTING NETWORKS

Jacques Oswald, Paris, France, assignor to Compagnie Industrielle des Telephones, Paris, France, a corporation of France

Application January 18, 1956, Serial No. 559,965

5 Claims. (Cl. 333—28)

The equalisation of the attenuation curves of cable sections with symmetrical or coaxial pairs is normally effected by means of well-known networks: equalisers, artificial lines, correcting networks, etc.

However, it is very useful to have available, in addition to the fixed correcting networks, adjustable correcting networks of which the attenuation curve can be modified as desired by a change of an impedance and even preferably of one or more resistances incorporated in the circuit diagram of the correcting network. Actually such networks make it possible to compensate the variations of attenuation as a function of the temperature, as also the residual distortions which may appear after a certain number of amplification sections.

As these networks must generally be connected between impedances which are comparable to pure resistances, constant image-impedances are imposed on them, which, moreover, make it possible to put them in series under easy conditions.

H. W. Bode has described a well-known class of correcting networks in French Patent No. 820,760, filed on January 30, 1937, and its first certificate of addition No. 49,867, filed on September 21, 1938.

Fig. 4 of the above mentioned certificate of addition represents a circuit diagram of a correcting network in a form which is particularly used, and which is reproduced in attached Fig. 1.

This correcting network consists of a symmetrical shunted T, comprising in each of its horizontal branches a resistance R, in the superior branch which is in shunt or parallel with both horizontal branches, the network Q₁ and, in the shunt branch a network Q₂, these networks being inverse in relation to the resistance R and respectively closed on variable resistances R_a and R_b so as to remain constantly inverse in relation to R. The shunted T therefore has the constant characteristic impedance R.

The same is also true of Fig. 5 of the aforementioned French certificate of addition, reproduced on attached Fig. 2, if there be added to the foregoing diagram, in the superior branch, a resistance R₁ in parallel with the input of Q₁ and, in the shunt branch, a resistance R₂ in series with the input of Q under the condition: R₁R₂=R².

The features of the invention are pointed out in the following description and drawings, in which:

Figures 1 and 2 represent circuit diagrams, known in the art, of correcting networks as mentioned above;

Figure 3 represents a circuit diagram of a shunted T correcting network according to the invention;

Figure 4 shows the circuit diagram of network Q appearing in Figure 3;

Figure 5 represents a correcting network comprising a differential transformer;

Figure 6 shows a correcting network as in Figure 3 in which a 4-terminal network Q is inserted for correcting the slope;

Figure 7 is a diagram representing the operation of the correcting network according to Figure 6;

2

Figure 8 shows a correcting network known in the art which can be compared to the one described in Figure 6;

Figure 9 is a modified form of the correcting network described in Figure 6;

Figure 10 is a diagram representing the operation of the correcting network according to Figure 9;

Figure 11 is a duplicate of Figure 3, and

Figure 12 represents the circuit diagram of network Q appearing in Figure 11.

10 The correcting network in accordance with the invention is characterised in this that it comprises a cut-all antimetric 4-terminal network, composed of a lattice-type network of which two opposite branches are reactive and inverse, the other branches being reduced to variable resistances of which the product remains equal to that of the reactances of the reactive branches.

At first, it is believed best to set forth the definition of certain terms as used herein in both the specification and claims.

20 An "antimetric quadripole" is a quadripole having a mean characteristic impedance which is constant, i.e., a quadripole whose product of image-impedances is constant.

A "cut-all" quadripole is a quadripole offering infinite impedance at all frequencies; consequently, a quadripole in which no coupling exists between the input and output terminals thereof, i.e., the impedance as seen from one of its pairs of terminals is completely different from the impedance disposed between the terminals of the other pair.

30 A "lattice-type cut-all antimetric filter" is, therefore, nothing else but a bridge in equilibrium, whose impedances of each of the groups of opposed branches form a constant product equal to the square of the characteristic impedance R₀ of the cut-all; such a filter is illustrated in its most general form in Figure 12 of the drawing in which the branches have impedance values of

$$Z_1 \text{ and } \frac{R_0^2}{Z_1}$$

40 and

$$Z_2 \text{ and } \frac{R_0^2}{Z_2}$$

In the schematic view of a correcting network according to the present invention, the branches

$$Z_2 \text{ and } \frac{R_0^2}{Z_2}$$

are constituted by adjustable resistances

$$R_a \text{ and } R_b = \frac{R_0^2}{R_a}$$

50 whereas the branches

$$Z_1 \text{ and } \frac{R_0^2}{Z_1}$$

55 are purely reactive in the special case examined herein.

A shunted T correcting network according to the invention of which the diagram is shown in attached Fig. 3, has the advantage over the correcting network according to the aforementioned certificate of addition 49867 of only using, instead of two networks Q₁ and Q₂, a single network Q in a circuit connected on the one side in shunt with the resistance R₁, and on the other via a resistance R₂ to the primary winding of a transformer of which the secondary winding is in the shunt branch of the T. The network Q is an antimetric four-terminal network of infinite attenuation carried out in the form, shown in Fig. 4, of a lattice, of which two opposite fixed branches have as impedances

$$Z \text{ and } \frac{R_0^2}{Z}$$

70 the other branches being composed of the variable re-

sistances R_a and R_b which are so selected that the product thereof

$$R_a \times R_b = \frac{R_0^2}{R_a}$$

The superior branch of the correcting network is therefore constituted by placing in parallel with R_1 the input impedance W_1 of Q, which is the input impedance with open circuit as well as the image-impedance by reason of the balanced mounting; the impedance seen from the other terminals is

$$W_2 = \frac{R_0^2}{W_1}$$

If α is the transformation ratio, the shunted T will certainly be of constant characteristic impedance R if

$$R \sin \alpha^2 = \frac{R^2}{R_1 R_2} = \frac{R^2}{R_0^2}$$

which requires

$$R_1 R_2 = R_0^2$$

The theory of this new type of correcting network will be given. Then the attenuation formulae obtained will be compared with those of the Bode correcting networks.

It is known that the shunted T-type four terminal network of characteristic impedance R with a superior branch Z_1 and with a shunt branch

$$Z_2 = \frac{R^2}{Z_1}$$

admits a transfer exponent $\theta = a + jb$ given by the formula:

$$(1) \quad e^\theta - 1 = \frac{Z_1}{R}$$

As has been indicated, Z_1 is constituted here by placing in parallel R_1 and the input impedance W_1 given by:

$$(2) \quad W_1 = \frac{R_a Z + R_0^2}{R_a + Z}$$

It is convenient to introduce the reduced impedances:

$$(3) \quad \begin{cases} \frac{W_1}{R_0} = w_1 & \frac{R_1}{R_0} = r_1 & \frac{R}{R_0} = r \\ \frac{R_a}{R_0} = r_a & \frac{Z_1}{R_0} = z_1 & \frac{Z}{R_0} = z \end{cases}$$

and to put:

$$(4) \quad z = \coth \Gamma$$

$$(5) \quad \rho = \frac{r_a - 1}{r_a + 1}$$

which enables us to write

$$(6) \quad W_1 = \frac{1 + \rho e^{-2\Gamma}}{1 - \rho e^{-2\Gamma}}$$

and consequently

$$(7) \quad z_1 = \frac{W_1 r_1}{w_1 + r_1} = \frac{r_1}{r_1 + 1} \frac{1 + \rho e^{-2\Gamma}}{1 - \frac{r_1 - 1}{r_1 + 1} e^{-2\Gamma}}$$

and by carrying into (1)

$$(8) \quad e^\theta - 1 = \frac{r_1}{r(r_1 + 1)} \frac{1 + \rho e^{-2\Gamma}}{1 - \frac{r_1 - 1}{r_1 + 1} e^{-2\Gamma}}$$

This formula shows that, for $\rho = 0$, that is to say $R_a = R_0$, the attenuation of the correcting network A_0 is constant at all frequencies and given by

$$(9) \quad e^{a_0} - 1 = \frac{r_1}{r(r_1 + 1)}$$

Let us form

$$(10) \quad e^\theta - e^{a_0} = \frac{r_1}{r(r_1 + 1)} \frac{2r_1 \rho e^{-2\Gamma}}{(r_1 + 1) - \rho(r_1 - 1)e^{-2\Gamma}} = (e^{a_0} - 1) \frac{2r_1 \rho e^{-2\Gamma}}{(r_1 + 1) - \rho(r_1 - 1)e^{-2\Gamma}}$$

$$(11) \quad e^\theta + e^{a_0} = \frac{2(r_1 + 1)e^{a_0} + 2\rho e^{-2\Gamma}(e^{a_0} - r_1)}{r_1 + 1 - \rho(r_1 - 1)e^{-2\Gamma}}$$

(12) Formula 11 is simplified by choosing r_1 by:

$$r_1 = e^{a_0}$$

hence it follows that

$$5 \quad (13) \quad r = \alpha = \frac{r_1}{r_1^2 - 1} = \frac{1}{2 \sinh a_0}$$

We then get from 10 and 11

$$10 \quad (14) \quad \frac{e^\theta - e^{a_0}}{e^\theta + e^{a_0}} = \tanh \frac{\theta - a_0}{2} = \rho e^{-2\Gamma} \tanh \frac{a_0}{2}$$

Formula 14 is strict, but its use a little laborious. It is possible to substitute for it a more easily handled approximate formula:

15 From this we get:

$$(15) \quad \theta = a_0 + 2 \operatorname{arc tanh} \left(\rho e^{-2\Gamma} \tanh \frac{a_0}{2} \right)$$

$$20 \quad = a_0 + \log \frac{1 + \rho e^{-2\Gamma} \tanh \frac{a_0}{2}}{1 - \rho e^{-2\Gamma} \tanh \frac{a_0}{2}}$$

For fairly small differences $\theta - a_0$, it is possible to use the classic development of the logarithm:

$$25 \quad 2\rho e^{-2\Gamma} \tanh \frac{a_0}{2} + \frac{8}{3} \rho^3 e^{-6} \tanh^3 \frac{a_0}{2}$$

restricting ourselves to the second term, the third being negligible in the existing conditions, which gives the sufficiently approximate formula:

$$30 \quad (16) \quad \theta \approx a_0 + 2\rho e^{-2\Gamma} \tanh \frac{a_0}{2}$$

By putting

$$35 \quad \Gamma = A + jb$$

and by separating the terms relating to the attenuation and the phase-shift, we get:

$$40 \quad (17) \quad \begin{cases} a \approx a_0 + 2\rho e^{-2A} \tanh \frac{a_0}{2} \cos 2B \\ b \approx -2\rho e^{-2A} \tanh \frac{a_0}{2} \sin 2B \end{cases}$$

It will therefore be seen that the attenuation of the 45 correcting network comprises in addition to the fixed portion a_0 , a portion proportional to

$$\rho e^{-2A} \cos 2B$$

50 At the frequencies for which B is an odd multiple of

$$\frac{\pi}{4}, \cos 2B$$

is zero, and a equals a_0 , whatever the value given 55 to the parameter of adjustment ρ : we have pivot points of the attenuation curves.

Choosing for Z a pure reactance, $jX(w)$, is Γ reduced to jB , with

$$60 \quad (18) \quad \cot B = -\frac{X}{R_0} = -x$$

The pivot points therefore correspond to the values $\pm j$ of the reduced reactance; there may be any number of them, and the number is reduced to one for an inductance or a capacity. We have:

$$(A) \quad a \approx a_0 + 2\rho \tanh \frac{a_0}{2} \cos 2B$$

The maximum differences occur at the frequencies for 70 which:

$$B = \frac{h\pi}{2}$$

that is, for the zeros and the poles of Z .

75 It may be pointed out that it is sufficient to reverse the

input and output terminals of the 4-terminal network Q in order to reverse

$$R_a \text{ and } R_b = \frac{R_0^2}{R_a}$$

This halves the number of regulating resistances, which has the advantage, not so much of effecting a saving as of reducing the number of regulating positions.

Other equivalent structures can be substituted for the bridged-T type circuit diagram which has been described.

The lattice-type structure is not economical, but the differential diagram thereof, as shown in Figure 5 is interesting.

It is determined by means of the lattice, by application of Bartlett's theorem of bisection. The impedance of the cut-all quadripole as seen from the transformer across the resistance R'_2 is called W'_2 , while the impedance of this quadripole as seen from the shunt branch R'_1 is designated W'_1 . The symmetrical lattice equivalent to the differential has as branches:

$$\frac{2}{\alpha'^2}(R'_2 + W'_2), \text{ and } ||2R'_1, 2W'_1||$$

(notation for placing in parallel).

That equivalent to the T has as branches.

$$R + 2\alpha^2(R_2 + W_2) \text{ and } \left| \left| R, \frac{R_1}{2}, \frac{W_1}{2} \right| \right|$$

It is therefore necessary that

$$(19) \quad \text{Lattice equivalent: } W'_1 = \frac{W_1}{4}$$

and, in order that:

$$(19') \quad \text{Differential: } W'_2 = \frac{W_2}{4}$$

it is necessary to take

$$(20) \quad \alpha' = \frac{1}{2\alpha} = \frac{1}{2r} = \frac{R_0}{2R}$$

The Equations 19 and 19' show that the quadripole Q' may be deduced from the quadripole Q by the reduction to one-quarter of the impedances of the branches. The character impedance R'_0 thereof is equal to

$$\frac{R_0}{4}$$

and one may, therefore, write:

$$(20') \quad \alpha' = \frac{2R'_0}{R}$$

On the other hand, R'_1 is equal to $\frac{1}{4} || 2R, R_1 ||$ that is in taking into consideration Equations 12 and 13, to

$$\frac{R_0}{4 \cosh \alpha_0}$$

or

$$\frac{R_0 R}{2\sqrt{R_0^2 + 4R^2}}$$

or again

$$\frac{R R'_0}{\sqrt{R^2 + 4R'^2}}$$

and R'_1 is equal to

$$\frac{R'_0^2}{R^2}$$

the quantities R'_1 and R'_2 on the one hand, and the quantities W'_1 and W'_2 , on the other, having the same product.

The Bode correcting networks give transfer exponents defined by the Formula 16 in which α_0 and ρ have the same meaning (reference attenuation and regulating parameter which in this case is the coefficient of disadaptation to the input of Q_1 and Q_2 but in which Γ is the transfer exponent (effective or on images) of Q_1 and Q_2 .

If the networks Q_1 and Q_2 are phase shifters, and if $Z=jX$ be the common value of the reactance of two opposite branches, we have:

$$5 \quad \coth \frac{B}{2} = j \frac{X}{R_0}$$

whence

$$(21) \quad \cot \frac{B}{2} = -\frac{X}{R_0} = -x$$

and we also have the formula (A):

$$(A) \quad a \approx a_0 + 2\rho \tanh \frac{\alpha_0}{2} \cos 2B$$

15 The pivots, however, correspond to the frequencies for which the modulus of the reduced reactance x is equal to

$$20 \quad \cot \frac{(2h+1)\pi}{8}$$

In this case, therefore, there are at least two pivots, and always an even number.

It will therefore be seen that the new correcting networks permit more freedom in the choice of the characteristic.

As has already been pointed out, the reversal of the input 4-terminals of the quadripole Q makes it possible to reduce the number of resistances by a simple arrangement, while this is not the case with the Bode correcting networks.

The following examples of use will make it possible to form a more complete judgment of the advantages of the correcting networks according to the invention, particularly with regard to saving in reactive elements.

35 First of all we will take the example of a slope-correcting network, of impedance equal to 150 ohms, admitting a pivot frequency f_0 of 68 kc./s. with an attenuation α_0 of 0.8 nepers, the correcting network being for use in a 12 to 68 kc./s. band:

40 Fig. 6 represents the simplest correcting network set up in accordance with the method described.

The reduced resistance

$$r = \frac{R}{R_0}$$

45 is equal to

$$\frac{1}{2 \sinh \frac{\alpha_0}{2}} = 0.563$$

50 This is the α ratio of the transformer R_0 is equal to 266Ω, R_1 to $R_0 e^{\alpha_0}$, that is 591 ohms, R_2 equal to

$$\frac{R_0^2}{R_1}$$

has the value of 120 ohms.

55 The antimeritic cut-all 4-terminal network Q , will allow for Z a capacitive branch, of reactance $-jR_0 = -266j$ for the frequency of 68 kc./s., which fixes the value of the capacity: $C = 8840 \mu F$ and of the inductance of the opposite branch: $L = CR_0^2 = 625 \mu H$.

60 The approximate Formula A here gives:

$$(22) \quad a \approx a_0 + 0.76 \rho \cos 2B$$

B being determined by:

65

$$(23) \quad \cot B = \frac{\omega_0}{\omega}$$

The exact formula has been applied for the maximum value $\rho = 1$.

The correction curves have been represented in full lines in Fig. 7 for the values $\rho = \pm 0.5$, $\rho = \pm 1$.

We will determine the corresponding Bode correcting network.

Let us choose for Q_1 an elementary phase shifter composed of a symmetrical inductance-capacity lattice.

The first pivot is defined, as has been seen, by

$$z(w_0) = \frac{1}{jCW_0R_0} = -j \cot \frac{\pi}{8} = -2.414j$$

hence

$$(24) \quad \cot \frac{B}{2} = \frac{1}{CwR_0} = 2.414 \frac{w_0}{w}$$

The application of the formulae previously given makes it possible to calculate the attenuation of the correcting network, the curves corresponding to $\rho \pm 0.5, \pm 1$ are represented in discontinuous lines in Fig. 7.

The determination of the elements is as follows:

The superior resistance is of 591 ohms, as in the correcting network according to the present invention; the resistance in the shunt branch of the T is equal to

$$\frac{150^2}{591} = 38.1\Omega$$

The networks Q_1 and Q_2 have $R_0 = 266$ ohms as constant characteristic impedance.

The Formula 24 gives the value of the capacity of the network $Q_1: C_1 = 3660 \text{ pF}$; that of the inductance L_1 is deduced therefrom by: $L_1 = C_1 R_0^2 = 260 \mu\text{H}$.

The inverse network Q_2 has inductances L_2 of 82 μH and capacities C_2 of 11,500 pF .

Fig. 8 represents the whole of the correcting network.

It will be seen that the correcting network according to the invention, if it requires a transformer only comprises an inductance and a capacity, while the Bode type correcting network comprises 4 inductances and 4 capacities.

The comparison of the attenuation curves shows their slight difference; nevertheless those of the correcting network according to the invention are more rectilinear, for the low values of ρ .

Again we will take the example of a curvature correcting network of the same impedance 150 ohms, admitting pivots at the frequencies 12 and 68 kc./s. with an attenuation a_0 of 0.42 N.

We have here:

$$\tanh \frac{a_0}{2} = \tanh 0.21 = 0.207$$

$$\alpha = \frac{R}{R_0} = \frac{1}{2 \sinh 0.42} = 1.157$$

hence

$$R_0 = 130\Omega, R_1 = R_0 e^{\alpha} = 197.5\Omega, R_2 = \frac{R_0^2}{R_1} = 85.5\Omega$$

The existence of the two pivots requires, as the simplest solution, the use of an auxiliary network of which the reactive branches are composed one of a resonant circuit (L, C), and the other of an antiresonant circuit (L', C').

The elements of the resonant circuit are immediately determined by the value $-jR_0$ of its impedance on the pivots:

$$L = \frac{R_0}{\omega_2 - \omega_1} = 0.37 \text{ mH}$$

$$C = \frac{\omega_2 - \omega_1}{R_0 \omega_1 \omega_2} = 84,000 \text{ pF}$$

Those of the anti-resonant circuit have the value:

$$L' = CR_0^2 = 1.418$$

$$C' = \frac{L}{R_0^2} = 21,860 \text{ pF}$$

Fig. 9 gives the diagram of the correcting network, Fig. 10 the attenuation curves for the same values of ρ as before. We have therefore seen that the method consisting of using "cut-all" four-terminal networks in the correcting network permits of advantageous results.

In the foregoing, a particular choice of "cut-all" networks has been indicated; we have assumed two oppo-

site reactive branches and two composed of resistances, of which the conjugate variation makes it possible to obtain adjustable variation attenuations.

It should be noted that, generally speaking, the use of "cut-all" four-terminal networks, with reverse opposite branches with the same ratio of inversion may be of interest in adjustable or fixed correcting networks.

Fig. 11 represents a correcting network of this kind in the form of a shunted T, R_1 may be infinite and R_2 zero. The general plan of the four-terminal network Q is given in Fig. 12: this is a lattice with opposite reversed branches, Z_1

$$\frac{R_0^2}{Z_1}$$

15 and Z_2 ,

$$\frac{R_0^2}{Z_2}$$

which branches may be purely reactive, purely resistive or comprise an assembly of reactive and resistive elements. The property of a four-terminal network of this kind to be capable of being substituted for the two four-terminal networks of the "Bode type" diagrams, by the use of its open-circuit impedances, seen from each pair 20 of terminals, may lead to a saving in the elements used in the setting up of the correcting network.

What is claimed is:

1. A correcting network with adjustable attenuation and having a constant characteristic impedance equal to 30 R , formed by a symmetrical bridged-T circuit comprising horizontal branches each having a resistance equal to R , a superior branch in parallel with said horizontal branches having a resistance equal to R_1 , an antimeritic cut-all lattice-type quadripole with one pair of the terminals thereof connected in parallel with said superior branch and having a characteristic impedance R_0 , whereby R_0 is related to R and R_1 by the equation

$$R_0^2 = \frac{RR_1^2}{R + R_1}$$

a transformer having a primary and a secondary winding and a ratio equal to

$$\frac{R}{R_0}$$

said secondary winding forming the shunt branch connected to the midpoint of the horizontal branches of said network, a resistance R_2 equal to

$$\frac{R_0^2}{R_1}$$

50 said primary winding being connected across a circuit including said resistance R_2 and the other pair of terminals of said quadripole, said cut-all lattice type quadripole including two opposite branches with adjustable resistances of which the product remains equal to R_0^2 and two other opposite branches having fixed impedances whose product is equal to R_0^2 .

55 60 2. A correcting network according to claim 1, in which said fixed impedances of said cut-all quadripole are reactances.

3. A correcting network with adjustable attenuation and having a constant characteristic impedance equal to 65 R , formed by a differential network equivalent to the T-type comprising a hybrid coil with two identical primary windings and a secondary winding, said two identical primary windings constituting the horizontal branches of said correcting network, a resistance R_2' , an antimeritic cut-all lattice-type quadripole having a characteristic impedance equal to R_0' , said secondary winding being connected to one pair of terminals of said quadripole in series with said resistance R_2' , said quadripole including two opposite branches with adjustable resistances whose product remains equal to $R_0'^2$ and two further opposite

branches with fixed impedances whose product is equal to $R_0'^2$, a shunt branch in said differential network including a resistance R_1' connected across the other pair of terminals of said quadripole, the values of R_1' and R_2' being equal to

$$\frac{RR_0'}{\sqrt{R^2 + 4R_0'^2}}$$

and

$$\frac{R_0'}{R} \sqrt{R^2 + 4R_0'^2}$$

respectively, and the ratio of the number of turns of said secondary winding to the number of turns of each of said primary windings being equal to

$$\frac{2R_0'}{R}$$

4. A correcting network according to claim 3, in which said fixed impedances of said cut-all quadripole are re- 20

5. A correcting network with adjustable attenuation and having a constant characteristic impedance equal to R , formed by a symmetrical T-type network having hori-

zontal and shunt branches, a transformer having primary and secondary windings, one of said windings being symmetrically connected in one of said horizontal and shunt branches of said network, impedance means symmetrical forming the other of said branches, an antimetric cut-all four terminal lattice-type quadripole having infinite attenuation and with a constant mean characteristic impedance, means including a resistance for connecting one pair of terminals of said quadripole to the other winding of said transformer, the other pair of terminals of said quadripole being connected across said impedance means, said quadripole having two branches including adjustable resistances whose product remains equal to the square of the characteristic impedance of said quadripole and two further branches including impedances whose product is also equal to the square of the characteristic impedance of said quadripole.
